Thomas Howe, ATTORNEY

UNITED STATES PATENT OFFICE.

SAMUEL N. CASTLE, OF NEW ROCHELLE, NEW YORK.

ELECTRIC FURNACE.

1,420,687.

Specification of Letters Patent. Patented June 27, 1922.

Application filed August 13, 1918. Serial No. 249,622.

To all whom it may concern:

Be it known that I, SAMUEL N. CASTLE, a citizen of the United States, residing at New Rochelle, Westchester County, State of New York, have invented new and useful Improvements in Electric Furnaces, of which the following is a specification.

This invention relates to electric furnaces of the induction type; that is, that type 10 wherein a heating current is magnetically induced in the charge.

The main object of the invention is to improve the metallurgical conditions of furnaces of the type referred to, particularly 15 those for making steel. A large surface of bath is desirable for refining purposes and also it is desirable that the greatest heat shall be generated at the surface. Accordingly bearing in mind that there is a large 20 leakage flux adjacent the windings and outside the core in apparatus of this character, I make the walls of the crucible sloping so as to give an increased surface of bath and the inducing windings are placed above the 25 bath so that the surface, being the nearest to the windings, has the greatest heat developed in it. The mounting of the winding above the bath and sloping the walls also have the practical advantages that if in the 30 one case the metal breaks through the lining it does not overrun and destroy the winding as it does where the winding is within or below the bath, and in the other case the sloping walls may be patched. With sub- 35 stantially vertical walls the patch would not stay in place. This greatly facilitates repairs. If the inducing magnetism is unevenly distributed across the bath, the unbalanced condition tends to cause electro- 40 dynamic action in the bath and if the inequality is sufficiently great a violent com- motion will take place whereas a gentle cir- culation resembling that of the crucible fur- nace is desirable; also if magnetism is con- 45 centrated to any considerable extent at one side of the bath the overheating of the lining at that side is harmful to it and unequal heating of the parts is liable to cause crack- ing. To avoid the disadvantages as indi- 50 cated, and which are especially liable to occur where the bath is wide, the inducing winding is distributed transversely of the bath so that the magnetism is so distributed as to achieve the desired results. These will 55 be such as to prevent any undue violence of

circulation in the bath and usually a uniform temperature gradient and heating transversely of the bath.

In addition to the objects as above indicated, other and ancillary objects of the invention will appear hereinafter.

In the accompanying drawings, which illustrate the invention,

Fig. 1 is a vertical axial section of a furnace embodying the invention.

Fig. 2 is a top plan view on a reduced scale, and

Fig. 3 is a side elevation, but with part in section, on the scale of Fig. 2, but viewed from a point ninety degrees removed from the view of Fig. 1.

Referring to the drawings, the apparatus comprises rockers 1 and 2, each of which rests on rollers 3 and 4. Supported by the rockers are the transformer core 5 of laminated iron and the annular crucible 6 containing the bath or charge 7. As will be seen, the crucible surrounds the central leg of the core 5 and extends between it and the two outer legs, and between the upper and lower yokes magnetically uniting the legs.

Secured to the top of the core are the rings 8, 9 and 10 from which depend bolts or rods 11 which support the bars or plates 12 and which in turn support the primary or inducing windings 13. The windings which are annular in top plan view, may be secured to these bars in any well known or suitable manner. The rods 11, or some of them are extended and are secured to the cover 14 of the crucible. This roof may be made in a single piece of bricks built up in arch form between the marginal bars 15 and 16 of circular form. The top yoke of the core, the windings and the cover of the crucible are thus secured together and can be removed and replaced as a unit. Eye pieces 17 and 18 secured to the top of the yoke provide a means whereby crane hooks can be engaged with the unit to lift it.

The crucible may be of materials commonly used in the art for this purpose, the refractory lining being frequently magnesite or dolomite. Also the construction of the crucible may conform to the knowledge of the art except that the side walls 19 and 20 are inclined so that increased surface of the bath and capability of patching the lining, as before referred to, are secured. As shown these

walls are at angles of approximately 45° with the vertical and horizontal and should not be at a less angle with the vertical than 15° in order to accomplish the desired results.

It will be observed that the entire winding of the apparatus is at a higher level than the bath so that if the latter breaks through the lining it will not destroy the winding. Also the location of the winding above the bath (the annular coils being directly above the annular crucible) produces greatest heat at the bath surface as before stated. The winding is so distributed transversely of the bath that the magnetic distribution across it is substantially uniform and a uniform temperature gradient across the bath is secured. This is secured in the structure illustrated by uniformly distributing the winding above the entire surface of the bath and even causing it to extend beyond the bath to some extent at the sides in order to insure that the desired distribution of magnetism shall extend completely to the sides of the bath. The advantages of this have been already referred to.

While the invention has been illustrated by a furnace intended to be operated by single phase current, it may be as readily made use of in polyphase apparatus as in single phase, only such differences in the structures being necessary as are well understood by those skilled in the art. Also the invention may have other embodiments without departing from its spirit, and is not therefore, limited to the structure shown in the drawings.

What I claim is—

1. An electric furnace of the induction type having a core, a crucible having sloping walls making angles of not less than 15° with the vertical for containing the bath interlinked with said core, windings interlinked with said core, and means for sup-

porting all of the windings at a higher level 45° than said bath.

2. An electric furnace of the induction type having a core, a crucible having sloping walls not less than 15° with the vertical for containing the bath interlinked with said core, and a winding interlinked with said core for inducing a current in said bath.

3. An electric furnace of the induction type having a core comprising a removable yoke, a crucible for containing the bath interlinked with said core and a winding interlinked with said core and secured to said yoke whereby said yoke and winding are removable together as a unit.

4. An electric furnace of the induction type having a core comprising a removable yoke, a crucible for containing the bath interlinked with said core, said crucible having a cover and a winding interlinked with said core, said yoke, winding and cover being secured together whereby they are removable as a unit.

5. An electric furnace of the induction type having a core, a crucible having sloping walls making angles of not less than 15° with the vertical for containing the bath interlinked with said core, windings interlinked with said core, and means for supporting all of the windings directly above said bath, said windings being uniformly distributed transversely of the bath.

6. An electric furnace of the induction type having a core, a crucible having sloping walls making angles of not less than 15° with the vertical for containing the bath interlinked with said core, windings interlinked with said core, and means for supporting all of the windings directly above said bath.

In testimony whereof I have signed this 24th day of April, 1918.

SAMUEL N. CASTLE.
